Filed Mar. 2, 1960, Ser. No. 59,594

Term of patent 14 years

(Cl. D54—12)

FIG.1

FIG.2

FIG.3

FIG.4

FIG.5

FIG. 1 is a back elevational view of a spoon showing my new design;

FIG. 2 is a side elevational view of the spoon;

FIG. 3 is a front elevational view of the spoon; and FIGS. 4 and 5 are sections on the respective lines 4—4 and 5—5 of FIG. 3.

The essential features of my design for a spoon or similar article reside in the configuration of the handle in combination with the particular type of ornamentation as applied thereto.

I claim:

The ornamental design for a spoon or similar article, substantially as shown and described.
